UNITED STATES PATENT OFFICE

HARRY E. GOSCH, OF NORTH TONAWANDA, NEW YORK, ASSIGNOR TO CREO-DIPT COMPANY, INC., OF NORTH TONAWANDA, NEW YORK, A CORPORATION OF NEW YORK

DRAINING APPARATUS

Original application filed August 18, 1928, Serial No. 340,466. Divided and this application filed July 29, 1929. Serial No. 382,024.

This invention relates to an apparatus for draining excess liquid from shingles and the like after the same have been immersed in a bath of liquid for staining or impregnating the same, this application being a division of an application for Letters Patent of the United States filed August 18, 1928, Serial Number 340,466.

The object of this invention is to provide a draining apparatus whereby excess liquid may be removed from bundles of shingles and the like readily, expeditiously, economically and thoroughly.

In the accompanying drawings:—

Figure 1 is a vertical longitudinal section of a draining apparatus embodying my invention.

Figure 2 is a vertical section of the same taken on line 2—2 Fig. 1.

Figure 3 is a vertical section, on an enlarged scale, taken on line 3—3 Fig. 1.

Figure 4 is a side elevation of the draining apparatus, on an enlarged scale, with the hood or enclosing casing removed.

Figure 5 is a vertical section taken on line 5—5 Fig. 4.

Figures 6, 7 and 8 are vertical sections taken on the correspondingly numbered lines in Fig. 3.

In the following description, similar characters of reference indicate like parts in the several figures of the drawings.

Any suitable means may be employed for dipping the bundles of shingles 32 in a liquid for the purpose of coating, staining or impregnating the same, such for example as the machine forming the subject of the U. S. patent application above referred to and comprising a dipping tank containing a bath of liquid into which the bundles are dipped after which the bundles are operated on by the present draining machine to remove the surplus liquid, which draining machine is constructed as follows:

This draining device comprises essentially a cage or openwork carrier which is adapted to receive the bundles of shingles or other articles and whirl the same rapidly about an axis so that the surplus liquid is removed by centrifugal force from the

shingles, and an enclosing casing or hood which catches the surplus liquid thus removed and permits of returning the same to the dipping tank for treating other bundles of material.

This rotary cage may be variously constructed but in its preferred form the same comprises a frame composed of a plurality of transverse end bars 125, 126 which are secured together at right angles to one another, and a plurality of longitudinal side bars 127 connecting corresponding parts of the end bars on diametrically opposite sides of the axis of this cage and forming two gateways or openings on diametrically opposite sides of this frame at right angles to the longitudinal walls formed by the bars 127.

Along the inner side of the longitudinal bars of this cage are arranged two rows of transverse rollers 128, these two rows being arranged on opposite sides of the axis of the cage and the members of each row being pivoted at opposite ends on the end bars of 127.

Arranged transversely on the inner sides of the end bars of the cage and secured thereto are two end walls 129 which are preferably constructed of sheet metal and in the space formed centrally between these two sets of end bars are arranged two trunnion blocks 130 which are provided with outwardly projecting horizontal transverse trunnions 131, 132 which are journaled in bearings 133 which rise from the main frame or base 134 of this draining device.

The gateways on diametrically opposite sides of the rotary cage may be opened and closed by means of gates which are preferably made of openwork form so that the same together with the body or frame of the cage form a reticulated closure for the bundles of shingles or the like, which may be placed within this cage, and permit the excess liquid to be stripped or drained from this material by centrifugal force and thrown through the openings in the cage upon rapidly whirling or rotating the latter about its horizontal axis.

Each of these gates of the draining cage 100

may be of any suitable form but the same, as shown in Figs. 1, 3, 5 and 8 preferably consist of two longitudinal side guide rails 135, a plurality of longitudinal intermediate gate bars 136, a plurality of transverse rods 137 connecting the side and intermediate bars 135, 136 at intervals, and a handle 138 secured to some of the intermediate bars at one end thereof and permitting of moving this gate manually into and out of its operative position. This gate is slideable horizontally with its guide bars 135 in engagement with a pair of guide rails 139, 140 mounted on the cage frame on opposite sides of one of the gate ways thereof, these guide rails being preferably provided with a corresponding pair of inner guide grooves 141 arranged near the axis of the cage, and a corresponding pair of outer guide grooves 142 arranged farther from the axis of this cage so that by engaging the guide bars 135 of each gate with the inner guide grooves 141, the width of the space within the cage between these gates will be reduced and adapt the same for treating bundles of shingles which are comparatively short, while upon engaging the guide bars 135 of the gates with the outer guide ways 142 of the guide rails on the cage, the distance within the cage between the gates will be correspondingly increased and adapt the cage for receiving bundles of shingles which are of correspondingly increased length.

It will thus be apparent that by thus shifting the gates for one set of these guide ways to the other, that the machine can be readily and conveniently adapted for treating bundles of shingles of various sizes or lengths without any material alteration in the construction.

The opening and closing of each gate way is accomplished by merely sliding the respective gate lengthwise in the corresponding guide grooves of the companion guide rails on the cage. The inward movement of each of these gates is limited so as to arrest the same when it is in the proper position for closing the respective gate way, this being preferably accomplished by providing one of the guide rails with a stop pin 143 which is engaged with the adjacent end of one of the guide bars on the gate, as shown in Fig. 5.

In order to lock each gate in its operative position across the respective gate way, means are provided consisting preferably of locking pins 144 which are guided to move transversely in one of the guide rails into and out of the path of the respective guide bar of the gate so as to engage the latter at that end thereof, opposite to that which is engaged by the stop pin 143, a cross bar 145 connecting the outer ends of the locking pins 144 and serving as a handle for manipulating these locking pins, a tension rod 146

arranged transversely at the front end of each gate way and guided at its opposite ends on the guide rails 139, 140 between the inner and outer guide grooves 141, 142 and connected at one end with the handle cross bar 145, as best shown in Figs. 5 and 8, and a retaining spring 147 surrounding the opposite end of this tension rod and bearing at one end against the adjacent guide rail 140 and at its opposite ends a shoulder 148 on this tension rod.

By lifting the stop pins 144 by means of the handle 145 in opposition to the spring 147 the front ends of both guide grooves 141, 142 are cleared, thereby permitting the attendant to withdraw the gate from either of these grooves for the purpose of opening the respective gateway of the cage.

When pushing the gate inwardly until it engages with the inner stops 143 of the respective guide way, the outer or front end of this gate will pass beyond the locking pins 144 and thereby permit the tension of the spring 147 to automatically move the locking pins 144 inwardly across the front end of the respective gate side bar, and thereby prevent the latter from becoming displaced during the subsequent operation of the machine.

When transferring bundles of shingles from the basket of the dipping or coating device to the cage of the draining device, the cage is brought to rest in a position in which one of the gateways thereof will be at the rear of the same and in line with the outlet of the dipping basket.

The forward movement of the bundle in the cage while being transferred into the same from the dipping basket is limited by the front gate of the cage which is closed at this time so that when both gates of the cage are closed the bundles will be securely held at their opposite ends against longitudinal displacement within the cage and also held in a substantially central position so that the cage is well-balanced and no material side thrust is exerted against the bearings or trunnions of the cage when rotating the same for stripping the excess liquid from the bundles of shingles by centrifugal force.

When the cage has been rotated for a sufficient length of time to properly drain the excess liquid from the shingles, the cage is again brought to rest and the front gate thereof is opened and the bundles of shingles therein are moved forwardly out of the cage and onto a transfer rack 170, and from the latter on to a platform 171 preparatory to being stacked, shipped or otherwise disposed of as desired. While the bundles of shingles are thus being discharged from the cage the latter is held at rest in a position in which its lower side is inclined toward the rack 170 so as to facilitate the removal of these

bundles, and the rack is also correspondingly inclined and in substantially the same plane as the lower side of the cage, while the latter is in its discharging position.

5 In the preferred construction of this rack the same includes a plurality of transverse rollers 271 which are pivotally mounted on side bars 172 constituting a part of the frame of this rack, so that a rolling surface

10 is provided over which the bundles of shingles may be easily moved from the draining cage to the delivery platform 171.

15 Rotary motion may be imparted to the cage by any suitable means but preferably by a driving belt 149 passing around a driven pulley 150 which is secured to an extension 151 of the trunnion 132 and therefore practically converts the same into a driving shaft, and also around a driving pulley 190.

20 This driving belt preferably moves continuously, and starting and stopping of the rotary movement of the cage is effected by tightening or loosening this belt 149 on the driving pulley 150 so that the same in effect forms the function of a clutch. In order to permit of thus utilizing this belt for this purpose, the same is made comparatively slack and the front stretch of the same is engaged by tightening pulley 152, which latter is mounted on a tightener rock arm 153 pivoted by means of a horizontal transverse pivot pin 154 to a bracket 155 on the adjacent part of the main frame of the machine.

25 30 35 Upon swinging this tightener arm 153 inwardly the tightener pulley 152 takes the slack out of the front stretch of the driving belt 149 and wraps the same sufficiently tight around the pulley 150, as shown by full lines in Fig. 6, so as to transmit motion from this belt to the driving pulley and cause the draining cage to rotate.

40 Upon swinging the tightener pulley 152 away from the belt 149 and pulley 150, as shown by dotted lines in Fig. 6, the belt is left sufficiently slack so that no motion is transmitted from the same to the pulley 150 and the cage connected therewith. The rocking motion of the tightener arm 153 is effected by means of a rock shaft 156 journaled horizontally and transversely on the lower front part of the main frame and provided with a rearwardly projecting rock arm 157 which is connected by means of a link or rod 158 with a lug 159 on the tightener arm 153, and a hand lever 160 secured to the rock shaft 156 and provided with a catch 161 adapted to interlock with different parts of a locking segment 162 for holding the belt tightener pulley 152 in either its operative position or its released position.

45 50 55 60 65 In order to arrest the rotation of the draining cage and also hold the same reliably in position while loading or unloading the same, a holding device is provided which

preferably consists of a brake drum 163 secured to the driving shaft 151, a brake band 164 passing around the upper part of the brake drum, and connected at its rear end by means of a pin 165 or otherwise to an adjacent part of the main frame, and a shifting rod or link 166 connecting the front end of the brake band 164 with the rock arm 157.

70 75 It follows from this construction that when the shifting rods 158 and 166 are raised the tightening roller 152 will wrap the belt tightly around the driving pulley 150 and the brake band 164 will be lifted or released from the brake drum 163 and thereby permit the power which is transmitted by the driving belt 149 to rotate the draining cage.

80 85 When, however, the shifting rods 158 and 166 are lowered by the rocking movement of the hand operated shaft 156 then the tightener pulley 152 will release the driving belt 149, but the brake band or strap 164 will be drawn tightly against the brake drum 163 and arrest the rotation of the driving shaft 90 95 151 and the cage connected therewith.

95 It will therefore be apparent that upon turning the hand lever 160 in one direction the drum will be released and caused to rotate while upon turning this hand lever in the opposite direction the power for rotating the cage will be thrown off and rotation of drum arrested, thereby materially simplifying the means for controlling the operation of this draining mechanism.

100 105 110 115 120 125 As the excess liquid is thrown off by centrifugal force from the bundles during the whirling or rotating action of the cage supporting these bundles, this projected liquid is caught by a casing which encloses the cage and the material contained therein. In the preferred form of this casing, as shown in Figs. 1, 2 and 3, the same comprises a lower stationary pan shaped section 167 arranged below the draining cage, and an upper vertically movable hood shaped section 168 which is adapted to be lifted above the cage and uncover the same, as shown by dotted lines in Fig. 1, for the purpose of enabling finished bundles to be discharged from the cage and fresh or undrained bundles to be placed therein, and this hood to be also moved downwardly into a position in which it encloses the cage in cooperation with the lower pan shaped section 167, as shown by full lines in Fig. 1, so that the excess liquid thrown off from the bundles which are rotated by the cage is intercepted by the inner sides of this casing and directed into the pan shaped lower section thereof.

130 In order to permit this hood 168 to move downwardly a sufficient extent so as to enclose the cage, the end walls of this hood are provided with vertical slots 169 which receive the bearings and trunnions of the cage

adjacent to opposite ends thereof, as best shown in Fig. 3. Escape of any of the liquid thrown off from the bundles of shingles through the slots 169 is prevented by means of guards or baffles 173 extending upwardly from the end walls of the pan 167 and across the slots 169 in the hood, as shown in Figs. 1 and 3, thereby avoiding waste of material.

10 The liquid thus recovered from the operation of draining the bundles flows from the bottom of the pan 167 into a trough 174 at one end thereof and from this trough this liquid is returned to the dipping tank by a 15 pipe 175, this pipe 175 being provided with a valve 176 for controlling the connection between the dipping tank and the pan section of the casing which encloses the draining cage.

20 To facilitate the raising and lowering of the hood 168 out of and into its operative position, means are provided which also serve to counter-balance the weight of this hood and thereby relieve the operator as well 25 as facilitating the covering and uncovering of the draining cage.

In the preferred form of means for accomplishing this purpose, shown in Figs. 1, 2 and 3, the same comprises a horizontal 30 shaft 177 journaled in suitable bearings on an overhead portion of the main frame, a pair of sheaves 178 secured to this shaft 177, lifting lines 179 each passing around one of the sheaves 178 and around a guide pulley 35 180 on an adjacent stationary part of the frame or building and having one end connected with the upper part of the hood 168, a counter-weight 181 secured to the opposite end of each shifting line 179, and a 40 shifting line 182 passing around a sprocket wheel 183 on the shaft 177 and provided with two depending stretches which are provided respectively with handles 184 and 185.

45 As the operator grasps one of these handles, for example 184, and pulls the same downwardly, the shaft 177 will rotate and lower the hood over the draining cage, while upon pulling downwardly upon the other handle 185, the shaft 177 will be turned in 50 the opposite direction and cause the hood to be raised and uncover the draining cage.

It will be obvious that this apparatus permits of thoroughly and rapidly removing the excess liquid from the bundles of shingles with a minimum expenditure of labor, power and expense.

I claim as my invention:

1. An apparatus for the purpose described, comprising a rotary reticulated cage having an opening for liquid treated articles and a plurality of guideways on said cage arranged different distances from the axis of said cage; and a gate for closing said opening and adapted to slide in one or 65 another of said guideways.

2. An apparatus for the purpose described, comprising a rotary reticulated cage having an opening for liquid treated articles and a guideway adjacent to said opening; a gate for closing said opening slideable in said guideway; a stop for limiting the inward movement of said gate in said guideway, and a catch for holding said gate in its closed position, comprising a locking pin mounted on the cage for movement into and out of the path of said gate, a tension rod guided on the cage and connected with said pin, and a spring interposed between said cage and tension rod and operating to yieldingly hold said pin in its operative 75 position.

3. An apparatus for the purpose described, comprising a rotary reticulated cage having an opening for liquid treated articles, rolling members within the cage for permitting said articles, to be easily introduced into and removed from the cage, means for holding the articles while in the cage, and a closure for said opening.

4. An apparatus for the purpose described, comprising a reticulated cage adapted to receive liquid treated articles and rotatable about a horizontal axis and having laterally projecting trunnions at its ends; bearings in which said trunnions turn; and a casing for enclosing said cage consisting of a pan shaped lower section arranged below the cage and a vertically movable hood shaped section arranged above the cage and provided with end walls 100 having slots which receive said trunnions; and said pan shaped section having upwardly projecting baffles extending across the slots in said hood shaped section.

In testimony whereof I hereby affix my 105 signature.

HARRY E. GOSCH.
